UNITED STATES PATENT OFFICE.

JOSÉ R. SISTO, OF MANZANILLO, CUBA.

APPARATUS FOR HANDLING INVALIDS OR PATIENTS.

1,121,673.

Specification of Letters Patent. Patented Dec. 22, 1914.

Application filed December 20, 1913. Serial No. 807,945.

To all whom it may concern:

Be it known that I, JOSÉ R. SISTO, a citizen of Spain, residing in Manzanillo, island of Cuba, have invented a new and useful 5 Apparatus for Handling Invalids or Patients; and I do hereby declare the following to be a full, clear, and exact description of the invention, such as will enable others skilled in the art to which it appertains to make and use the same.

This invention relates to the art of medical or hospital appliances, and particularly to a new and useful improved apparatus for the handling of invalids or patients.

15 As an object of the invention, it is the aim to provide an apparatus, not only whereby an invalid or patient may be comfortably supported during sickness or the like, but an apparatus including means 20 whereby the invalid or patient may be transferred or transported from the invalid bed to the operating room on a rolling operating table, without manually handling the invalid or patient, and without injury.

25 In practical fields, the details of construction may be subjected to alterations, falling within the scope of what is claimed.

The invention comprises further features and combination of parts, as hereinafter set 30 forth, shown in the drawings and claimed.

In the drawings:—Figure 1 is a view in perspective of the invalid bed constructed in accordance with the invention. Fig. 2 is a transverse sectional view through the under or supporting cloth of the invalid bed. Fig. 3 is an end view of the invalid bed, showing the operating table disposed under the under or supporting cloth of the bed, ready to receive the patient from the supporting cloth, the frame to which the supporting cloth is attached and the cloth are shown in section. Fig. 4 is a perspective view of the operating table. Fig. 5 is a fragmentary view of a portion of the invalid bed showing the slabs of the operating table supported in a frame of the invalid bed, said frame being connected to a lift. Fig. 6 is a detail perspective view of the frame for supporting the slabs of the operating table. Fig. 7 is a bottom plan view of the slabs of the operating table. Fig. 8 is an enlarged detail view of a portion of one of the slabs showing parts in section. Fig. 9 is a detail sectional view of another portion of one of the slabs. Fig. 10 is a detail sectional view

of the side bars or rods of the operating table, showing a trough or gutter supported upon the side rods of the table, and the slabs of the table held at angles to one another and supported in the gutter or trough. 60 Fig. 11 is a detail perspective view of the slabs of the operating table held at angles to one another. Fig. 12 is an enlarged detail sectional view through a portion of the frame for supporting the under or supporting cloth. Fig. 13 is a detail perspective view of one corner of the supporting frame for supporting the under or supporting cloth, showing the arms which guide said frame on the guide rods of the frame of the 70 invalid bed. Fig. 14 is a detail perspective view of the trough or gutter shown in Fig. 10. Fig. 15 is a detail sectional view showing the connections between a removable end brace bar and one of the vertical standards of the invalid bed.

Referring more particularly to the drawings, 1 designates the base frame of the invalid bed, which may be any suitable construction or shape, and is provided with 80 sockets 2 at the corners. Secured in the sockets 2 in any suitable manner are guide standards 3, which extend vertically, and terminate in arching portions 4 extending toward the center of such frame and fitting 85 a four-way union 5. This union 5 is disposed substantially centrally of such frame, and has a pulley 6 extended therefrom. The lower portions of the standards 3 adjacent the sockets 2 are braced or reinforced 90 by the rods 7. The end bar 8 is provided at its ends with downwardly extending hooked portions 9, which enter the pockets 10 of two of the vertical standards 3. It will be seen that this end bar 8 may be removed, 95 for the purpose hereinafter set forth. The upper portions of the vertical standards 3 are reinforced by the rods 11. Mounted in bearings 12 of two of the end guide standards 3 is a shaft 13 having a crank 14, and 100 on which shaft 13 a drum or the like 15 is mounted to rotate therewith. Carried by one of the rods 11 is a pulley 16.

Guided upon the standards 3 is a lift frame 17, the diagonal opposite corners of 105 which are braced by the spider frame 18. The frame 17 and spider frame 18 are integrally constructed, the vertical standards 3 passing through openings 19 of the frame 17. A cable or the like 20 is connected to 110

an eye 21 of the spider frame 18, and passes over the pulleys 6 and 16, and is wound about the drum 15. By rotating the shafts 13 by means of the crank 14, the lift frame 5 may be raised and lowered. A frame 22 substantially rectangular in contour is provided, the bars of which are angular in cross section and the horizontal portions 23 of said bars of the frame 22 are provided with 10 perforations 24. The longitudinal bars of the frame 22 are provided with slots 25, which receive the straps 26, which are provided with buckles 27, whereby the straps may be tightened. Adjacent the corners of 15 the frame 22 staples 28 are arranged to receive the arms 29, which are held in place by the screws 30. These arms 29, as will be observed extend at right angles to one another, so that the vertical bars 3 are received 20 therebetween, so as to guide the frame 22, when being raised or lowered. The vertical standards 3 are provided with apertures 31 to receive the pins 32, which are disposed beneath the arms 29, in order to support the 25 frame 22 in adjusted positions. The under or supporting cloth comprises thick blankets 33 having a covering of comparatively thin soft linen 34. The outer longitudinal portions and end portions of the blankets and 30 the linen coverings are bound together by the substantial borders 35 and canvas strips 36 stitched together by the stitching 37, the borders 35 being on the top and the canvas strip on the bottom. Passing through the 35 borders, the linen covering, the blankets and the canvas strips are eyelets 38. The adjacent portions of the blankets are stitched at 39 to the coverings. Arranged in the blankets and the coverings at their 40 adjacent parts are eyelets 40. A silk cord or the like 41 is interlaced through the eyelets 40, securing the adjacent parts of the blankets together, while any suitable cord or the like 42 is interlaced through the eyelets 38 and the perforations 24 of the frame 22, thereby connecting the blankets to the frame 22. The frame 22 is provided with 45 rings 43, while the lift is provided with similar rings 44. Connected to the rings 44 are cables or cords 45 and 46 having hooks 47 at their lower ends. When it is desired to raise and lower the frame 22 in the manner to be hereinafter set forth, the hooks are placed in engagement with the rings 43, 50 then the shaft 13 is rotated, which will raise and lower the lip 17 by means of the cable 20. The cables or ropes 46 are arranged adjacent the head of the invalid frame, and by tying a knot or two in said cables 46, the 55 head portions of the frame 22 may be held a little higher than the foot portion of the frame 22. It is also apparent that after the frame 22 has been raised to the desired height and the hooks 47 detached from the 60 rings 43, the head portion of the frame 22 65

may be supported in its adjusted position a little higher than the foot portion, by arranging the pins 32 at the head portion of the frame of the invalid bed, a little higher than the pins at the other end. The straps 70 75 76 reinforce the under or supporting blankets, as will be observed.

In connection with the invalid bed when performing operations or the like, any suitable operating table may be used, for instance such as shown in Fig. 4, said operating table 50 having rollers 51, the shelf 52 and the side rods 53 provided with upturned ends 54. This operating table is provided with removable table slabs 55, constructed of any suitable material, for instance such as glass. Held adjacent but spaced apart from the outer longitudinal edges of the glass slabs by means of the plates 56 (which are secured at 57 to the slabs) are rods 58. These rods 58 are constructed with oppositely arranged slots 59. Passing through the slots 59 are headed bars 60. Passing through an aperture of one end of each of said bars 60 is a pin or key 61, to hold the bars 60 in place, as well as preventing the separation of the slabs. The slabs together with the rods 58 are supported upon the transverse bars 63, which have curved ends 64 to engage the side rods or bars 53 of the 90 frame of the operating table.

When it is desired to remove the patient or invalid from the under or supporting cloth and convey him to the operating room upon the operating table, the frame 22 is 100 raised sufficiently, thereby permitting the operating table to be rolled under the supporting cloth, the rod 8 having first been removed. Then the frame 22 is lowered, until the supporting cloth engages the slabs. The straps 26 are then removed, after which the silk cord 41 is withdrawn from the eyelets, subsequently to which the frame 22 may be raised sufficiently, to permit the blankets or supporting cloth to separate, thereby 105 leaving the patient or invalid upon the slabs. The operating table then may be rolled to the operating room. After the patient or invalid has been operated upon, and it is desired to return the patient to the invalid bed, the operating table is rolled back to the invalid bed in the position shown in Fig. 3, then another frame 67 as shown in Figs. 5 and 6 having hooks 68 and rings 69, is inserted in the invalid bed frame in 110 the manner shown in Fig. 5, the arms 70 similar to the arms 29 acting to guide the frame 67. Then the slabs of the operating table are raised with the patient thereon, and the rods 58 placed in engagement with the hooks 68, as shown in Fig. 5. The frame 22 is again placed in the invalid bed frame 115 underneath the operating table slabs, the pins 32 again engaging the arms 29 to support said frame 22. The operating table 120 125 130

slabs are then lowered until they almost engage the under or supporting cloth, and then the headed bars 60 are removed, thereby permitting the slabs to be separated, in which case the patient or invalid will again rest upon the under or supporting cloth. The arms 70 are secured in place in a manner similar to the arms 29, as shown at 28¹ and 30^a. In raising the frame 67, the hooks 47 engage the rings 69.

If desired the operating table slabs may be held at angles to one another, by means of the angular headed bars 72 in lieu of the bars 60. These bars 72 are secured in place by the pins 73, in a manner similar to the holding of the bars 60. The slabs are held at such angles for the purpose of giving douches, or irrigating certain parts of the invalid's body or baths or the like, and when conducting such operations a gutter or trough 78 as shown in Figs. 10 and 14 is used, one end of which is designed to be arranged lower than the other, so that irrigation or douche fluid will run into some suitable receptacle (not shown).

From the foregoing it is apparent there has been devised an efficient, essential and desirable invalid bed, so constructed and used in combination with the suitable operating table, whereby the patient may be transferred from the bed chamber to the operating room and vice versa, without manually handling the patient, which not only renders the apparatus desirable, but practical.

The invention having been set forth, what is claimed as new and useful is:—

1. In an appliance for the support of invalids, a rectangular skeleton frame, an auxiliary rectangular frame adjustably supported in the first frame, an invalid supporter proper having connections with the auxiliary frame, said invalid supporter proper comprising two parts designed to be disconnected at their adjacent edges to permit the invalid to pass therebetween to rest upon another supporter, and means for detachably connecting the adjacent edges of said parts.

2. In an appliance for the support of invalids, a rectangular skeleton frame, an auxiliary rectangular frame adjustably supported in the first frame, an invalid supporter proper having connections with the auxiliary frame, said invalid supporter proper comprising two parts designed to be disconnected at their adjacent edges to permit the invalid to pass therebetween to rest upon another supporter, and means for detachably connecting the adjacent edges of said parts, and means for raising and lowering said auxiliary frame.

3. In an appliance for the support of invalids, a dominant rectangular skeleton frame, an auxiliary rectangular frame, arms

carried by the corners of the auxiliary frame and extending at right angles to each other between which the corner posts of the dominant frame engage, devices carried by said corner posts of the dominant frame for engaging under said arms for holding the auxiliary frame in adjusted positions in the dominant frame, an invalid supporter proper having connections with the auxiliary frame, said invalid supporter proper comprising two parts designed to be disconnected at their adjacent edges to permit the invalid to pass therebetween to rest upon another supporter, and means for detachably connecting the adjacent edges of said parts.

4. In an appliance for the support of invalids, a dominant rectangular skeleton frame, an auxiliary rectangular frame, arms carried by the corners of the auxiliary frame and extending at right angles to each other between which the corner posts of the dominant frame engage, devices carried by said corner posts of the dominant frame for engaging under said arms for holding the auxiliary frame in adjusted positions in the dominant frame, an invalid supporter proper having connections with the auxiliary frame, said invalid supporter proper comprising two parts designed to be disconnected at their adjacent edges to permit the invalid to pass therebetween to be received upon another supporter, and means for holding the adjacent edges of said parts together, and means for raising and lowering said auxiliary frame.

5. In an appliance for the support of invalids, a rectangular skeleton frame, an auxiliary rectangular frame adjustably supported in the first frame, an invalid supporter proper having laced connections with the auxiliary frame to support the same therewithin, said auxiliary frame having transverse straps to additionally support said invalid supporter proper, said invalid supporter proper comprising two parts designed to be disconnected at their adjacent edges to permit the invalid to pass therebetween to be received by another supporter, a lacing for detachably connecting the adjacent edges of said parts, and means for raising and lowering the auxiliary frame.

6. In an appliance for the support of invalids, a dominant rectangular skeleton frame, an auxiliary rectangular frame, arms carried by the corners of the auxiliary frame and extending at right angles to each other between which the corner posts of the dominant frame engage, devices carried by said corner posts of the dominant frame for engaging under said arms for holding the auxiliary frame in adjusted positions in the dominant frame, an invalid supporter proper having laced connections with the

auxiliary frame to support the same there-
within, said auxiliary frame having trans-
verse straps to additionally support said
invalid supporter proper, said invalid sup-
porter proper comprising two parts de-
signed to be disconnected at their adjacent
edges to permit the invalid to pass therebe-
tween to be received by another supporter, a
lacing for detachably connecting the adja-

cent edges of said parts, and means for 10
raising and lowering the auxiliary frame.

In testimony whereof I have signed my
name to this specification in the presence of
two subscribing witnesses.

JOSÉ R. SISTO.
